UNITED STATES PATENT OFFICE.

JOHN MURPHY, OF BROOKLYN, NEW YORK.

DESIGN FOR A RUBBER MAT.

SPECIFICATION forming part of Design No. 16,574, dated March 16, 1886.

Application filed November 3, 1885. Serial No. 191,789. Term of patent 14 years.

To all whom it may concern:

Be it known that I, JOHN MURPHY, of Brooklyn, county of Kings, and State of New York, have invented a certain new and original Design for the Ornamentation of India-Rubber Mats, Matting, or Carpeting, of which the following is a specification, reference being had to the accompanying drawing.

The nature of my design is clearly represented in the drawing, which shows a section of mat or matting embodying the same. Such design consists of an embossed surface for perforated mats or matting having conical bosses or protuberances laid in juxtaposed rows, each boss projecting up from the material below independent of any other, and forming channels or furrows between each row of cones and its immediate neighbor. The larger blackened figures in the illustration represent border perforations of cross shape and an inclosed panel having perforations of quarterfoil shape.

By the combination of specified surface and the perforations a matting is produced of quite marked beauty, developed by the variety of effects in light and shade upon the elaborated design, the embossed surface being brought into bold and effective relief.

What I claim as new, and desire to secure by Letters Patent, is—

The design for rubber mat herein shown and described, consisting of a surface ornamentation of pyramid projections, a border of one or more rows of perforations of cross-shape, and a panel having one or more rows of quarterfoil perforations.

JOHN MURPHY.
